UNITED STATES PATENT OFFICE.

LOUIS JOHN STEELE AND EDGAR FROSTICK KENT, OF PORTSMOUTH, AND GEORGE ALBERT MADDEN, OF SOUTHSEA, ENGLAND.

FURNACE GRATE.

Application filed March 20, 1923. Serial No. 626,353.

To all whom it may concern:

Be it known that we, LOUIS JOHN STEELE, EDGAR FROSTICK KENT, and GEORGE ALBERT MADDEN, subjects of the King of Great Britain and Ireland, residing, respectively, at 5 The Parade, H. M. Dockyard, Portsmouth, in the county of Hants, England, 49 Ophir Road, Portsmouth, in the county of Hants, England, and 51 Winter Road, 10 Southsea, in the county of Hants, England, have invented certain new and useful Improvements Relating to Furnace Grates, of which the following is a specification.

This invention primarily relates to stokers 15 of the travelling grate type in which longitudinally or transversely disposed grate bars are carried within so called caps or frames that are transversely disposed in parallel lines and are removably secured to transversely disposed bars connected together to form an endless conveyor, the uppermost part of which forms the grate on which the fuel is burnt, the conveyor being periodically moved whereby the fuel is received 25 on the grate as it passes into the furnace and carries the fuel forward towards the end of the combustion chamber where the clinker and ashes are discharged.

In such a type of stoker, the air admitted 30 in any desired manner and at any desired point passes beneath the grate, and then through the interstices between the grate bars in the caps or frames. Owing to the severe and destructive conditions which obtain when the coal is burnt on metallic surfaces, the grate bars in operation frequently become fused together and to the frames or caps in which they are carried, with the result that the supply of air becomes inadequate and thus in the movement of the grate through the furnace, the fuel is not completely consumed, whereby waste of fuel and inefficiency result.

The invention has for its object to avoid 45 this disadvantage by the provision of the bars integral with the so-called caps or frames and of such a form that fusion of the metal of the bars is avoided.

Thus according to the invention the grate 50 bars are integrally formed with the caps or frames and the interstitial spaces between the bars, and between the bars and the parallel disposed ends of the frame, gradually increase in width from the bottom to the 55 top or alternatively are made parallel to

suit certain grades of coal, so that thus all these spaces diverge upwardly and the air passing through them is widely diffused. In intermediate positions transverse to the grate bars and also on the opposite sides of the cap or frame, partitions or walls are integrally provided which protrude downwardly to form strengthening ribs which also increase the heat radiating and conducting surfaces, by which the integral frames and bars are kept cool.

Furthermore according to the invention the tops of the bars are fluted.

By such means it will be understood that the air in passing up through the interstitial spaces between the bars is widely diffused, the radiating surface is increased and the burning of the bars is prevented.

The invention is widely applicable to furnace grates.

A construction of furnace grate provided according to the invention is illustrated in the accompanying drawings in which—

Figure 1 is a detail elevation showing two of the caps or frames in which are disposed the grate bars.

Figure 2 is a plan view corresponding to Figure 1.

Figure 3 is a transverse section on the line X X of Figure 1.

It will be understood that in carrying the invention into effect the caps or frames are mounted upon any desired construction of endless supporting chain or carrier to form the travelling grate. In the construction of endless chain or carrier diagrammatically represented in the drawings a series of pairs of links *a* pivoted upon spindles *b* serves to carry transversely disposed cap or frame supporting bars *c*. Each of the said bars *c* supports a series of the caps or frames *d* in which are integrally formed the grate bars *e* in accordance with the invention. Each cap or frame *d* is provided with a downwardly extending lug *d¹* in which is formed a square hole for the reception of the square shank of a bolt *f* by which the cap or frame is secured in position upon the supporting bar *c*. The latter is advantageously formed with upstanding lugs *g* of rectangular form adapted to fit within correspondingly shaped recesses *h* formed in the lower edges of the downwardly depending portions of the adjacent caps or frames *d*.

Each cap or frame *d* is formed with a se-

ries of grate bars *e* extending longitudinally, the said bars being of a cross-section increasing from the lower edge to the upper surface and being disposed in such manner 5 that the interstitial spaces *i* between the adjacent bars also gradually increase in width from the bottom to the top. By reason of what may be termed the radial disposition of the grate bars in each cap or frame, the 10 air passing through the grate from beneath is well diffused or distributed in a fan-wise manner through the fuel. Transverse partitions *j* are formed at intervals across the width of the caps or frames and serve to 15 strengthen and support the grate bars. They are advantageously extended downwards as at *j*¹ to give increased strength and also to increase the heat radiating surface. The upper faces of the grate bars *e* are advantageously fluted. This serves to permit the 20 collection of dust thereon and thus to prevent clinker from directly adhering to the bars. Any clinker formed is readily removed by reason of the intermediate layer 25 of dust. Each of the cap or frame supporting bars *c* carries a series of the caps or frames extending the length of the bar which is determined according to the width of the furnace to which the grate is applied. 30 The caps or frames are identical with the exception of those at each end of the series which are specially formed for this purpose.

As indicated in Figure 1 the end cap or 35 frame is extended and provided with a massive end wall *k* having an inner face formed to a hyperbolic curve or surface and an outer face formed with an inclined surface *l* upon the depending portion which may serve to 40 rest upon guides provided at the side of the grate. The said end caps or frames are also provided with rectangular recesses *m* of the full size to receive the corresponding up- 45 standing lug *g* of the supporting bar.

It will be understood that the invention is 45 not limited in application to any particular type of travelling grate, nor to any particular means of supporting and moving the caps or frames, nor to the manner of mounting them upon the transverse supporting bars hereinbefore described. The invention 50 is further applicable with advantage to the construction of fixed grates.

We claim:

1. A furnace grate of the travelling type, 55 comprising grate elements consisting of frames having integral straight end walls and a plurality of integral transversely disposed grate bars extending between said end walls, said transversely disposed grate bars 60 being wider at the top than at the bottom, and having the interstitial spaces between them diverging outwardly towards opposite sides upwardly, and a conveyor upon the transversely disposed members of which the 65 said grate elements are supported in transverse series and members disposed at one side of said frames and integral therewith by which said frames are supported upon said conveyor, substantially as described. 70

2. A furnace grate of the travelling type, comprising grate elements consisting of frames having integral straight end walls and a plurality of integral transversely disposed grate bars extending between said end 75 walls, said transversely disposed grate bars being wider at the top than at the bottom and having the interstitial spaces between them diverging outwardly towards opposite sides upwardly, and having their upper faces 80 grooved, and a conveyor upon the transversely disposed members of which the said grate elements are supported in transverse series and members disposed at one side of said frames and integral therewith by which said frames are supported upon said conveyor, 85 substantially as described.

3. A furnace grate of the travelling type, comprising grate elements consisting of frames having integral straight end walls and intermediate partitions, and a plurality of integral transversely disposed grate bars extending between said end walls, said transversely disposed grate bars being wider at 90 the top than at the bottom and having the interstitial spaces between them diverging outwardly towards opposite sides upwardly, the said partitions extending downwardly 95 beyond the said grate bars, and a conveyor upon the transversely disposed members of which the said grate elements are supported in transverse series, substantially as described. 100
